(57) **CLAIM**

The ornamental design for a vehicle body and/or replica, as shown and described.

DESCRIPTION

FIG. 1 is a left, front perspective view of a vehicle body and/or replica showing my new design;

FIG. 2 is a right, front perspective view thereof;

FIG. 3 is a left, rear perspective view thereof;

FIG. 4 is a right, rear perspective view thereof;

FIG. 5 is a front elevational view thereof;

FIG. 6 is a rear elevational view thereof;

FIG. 7 is a left side elevational view thereof;

FIG. 9 is a top plan view thereof; and,

FIG. 10 is a bottom plan view thereof.

The portions of the vehicle shown in broken lines are for environmental and illustrative purposes that form no part of the claimed design.
